(57) **CLAIM**

The ornamental design for an end portion of a snack chip, as shown and described.

DESCRIPTION

FIG. 1 is a front perspective view of an end portion of a snack chip showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The dashed broken lines in FIGS. 1-8 form no part of the claimed design.

The dash-dot broken lines in FIGS. 1-3 and 6-8 are boundary lines and form no part of the claimed design.
